UNITED STATES PATENT OFFICE.

JOHN TALIAFERRO THOMPSON, OF NEWPORT, KENTUCKY, AND HENRY HAVELOCK CUMMINGS, OF NEWTON, MASSACHUSETTS; SAID CUMMINGS ASSIGNOR, BY MESNE ASSIGNMENTS, OF ONE-HALF TO THOMAS FORTUNE RYAN, OF NEW YORK, N. Y.

CARTRIDGE-MAGAZINE.

1,353,092.

Specification of Letters Patent. Patented Sept. 14, 1920.

Application filed June 7, 1920. Serial No. 386,994.

To all whom it may concern:

Be it known that we, JOHN TALIAFERRO THOMPSON and HENRY HAVELOCK CUMMINGS, citizens of the United States of 5 America, and residents, respectively, of Newport, in the county of Campbell and State of Kentucky, and Newton, in the county of Middlesex and State of Massachusetts, have invented new and useful Improvements, in 10 Cartridge-Magazines, of which the following is a specification.

The present invention relates to a new and improved cartridge magazine of the rotary type, combining with its function as a magazine that of lubricating the ammunition 15 which it contains.

Lubrication of metallic cartridge cases has been found highly desirable in the use of many types of firearms utilizing such ammunition. The cartridge cases are formed of 20 relatively soft metal and are urged into intimate engagement with the cartridge chamber by the very high powder pressure caused by the ignition of the propelling charge. 25 Slight irregularities in the surface of the chamber or in the sizing or formation of the cartridge are often sufficient to cause difficulty in extraction of the empty case after firing, by greatly increasing the friction between the case and the chamber.

This difficulty is at times so great that the cartridge casing is ruptured in the endeavor to extract it and a broken portion remains in the chamber. This is particularly true in the case of automatic or semi-automatic guns where the shell is started rearward very suddenly, often before the chamber pressure has been reduced to atmospheric, and in such cases the friction is increased by this pressure.

The friction between the case and chamber, even if it does not cause a rupture with consequent jam, is a source of constant wear and causes gradual change in the chamber 45 size which in turn increases the friction and danger of rupture and jam.

It has been heretofore proposed to lubricate cartridges at the time of making or before placing them in the magazine. These 50 methods are open to many objections in that if the lubricant used has sufficient body to remain effective for a considerable length of time it will be so heavy as to gum the gun

after firing any extended number of rounds. Further such lubrication makes the cartridge more difficult to handle, and the lubricant has a tendency to cause foreign matter to adhere to the cartridge with consequent deleterious effect upon the gun. 55

It is necessary in order for it to be successful that any method of lubrication be accomplished automatically in the normal operation of the gun for the reason that speed of operation is of vital importance, and further because of the tendency of the 60 user of the gun to neglect any action not directly involved in the use of the piece.

Heretofore where rifles or automatic guns have been supplied with a magazine of greater capacity than that which can be furnished by the usual box magazine placed within the gun contour, the larger magazines have been of the box type and have extended below the gun. Magazines of this character are objectionable for many reasons as they 70 are constantly liable to injury in striking against objects and also render the piece 75 awkward to handle.

The principal objects of the present invention are to overcome the aforesaid and other 80 difficulties and to provide a magazine which fulfills the requirements which have been set forth. It is an object to provide a magazine which will positively lubricate the cartridge it contains, the lubrication taking 85 place in the normal use of the magazine. It is also an object to provide a lubricating device which is self-feeding, which will require renewal of the lubricant only at comparatively long intervals and which will be 90 relatively easy to charge with lubricant. It is a further object to provide a magazine of the rotary type which may be fitted to rifles of usual design without material change in 95 their structure, which will be compact and simple in its construction, and contain and deliver properly more cartridges than the usual box magazine. It is an additional object to provide a device simple in construction and relatively inexpensive to manufacture. Other and further objects will appear 100 as the description proceeds.

We have illustrated a preferred embodiment of our invention in the accompanying drawing in which:

Figure 1. is a side elevation of the maga- 105

zine, broken away portions of a gun being shown to illustrate the method of attachment.

Fig. 2. is a cross section on line 2—2 of Fig. 1.

Fig. 3. is a side view of the rear attachment device.

Fig. 4. is a bottom view of the rear attachment device.

10 Fig. 5. is a perspective view of the forward attachment device.

Fig. 6. is a perspective view of the clip loading device.

15 Fig. 7. is a longitudinal section of the magazine.

Fig. 8. is a forward end view.

Fig. 9. is a rear end view.

Fig. 10. is a cross section on line 10—10 of Fig. 7.

20 Fig. 11. is a forward end view of the follower, and

Fig. 12. is a side view of the follower and the bearing ring member.

The magazine comprises a cylindrical casing 14 in which is secured the cylindrical oil reservoir 15, by means of screws 16. The forward end of the casing is provided with the central closure 17 having a check valve 18 therein. The rear end of the cage or rotor

25 20 is provided with sockets containing the balls 23 and the forward portion with sockets containing the larger balls 24. The balls are retained in place in the cage by upsetting the adjacent corners of the sockets in the cage. The cage 20 is restrained against longitudinal movement by the shoulder 25 on the oil reservoir 15 and the forward face of the follower actuating cup 26. This cup is retained in place on the pivot 19 by the 30 sleeve 27, the sleeve being held in position by the cotter pin 28.

The inner portion of the sleeve 27 is circular in cross section and has the outwardly extending lug 29 which engages the inner 45 end of the watch spring 30 surrounding the sleeve. The spring is contained within the cup 26 and its outer end is engaged by the stud 31 as shown in Fig. 9.

The follower comprises the longitudinal member 32 extending from the cup 26 to the forward bearing ring 33, the longitudinal member having fitted thereto the pusher member 34 which contacts with the cartridges as shown in Fig. 2. Secured by

50 screws to the face of the ring member 33 is the spring member 35, this member having the opening 36 retaining in place the lug 36' which is resiliently pressed into engagement with the ball contact 37. This

55 60 ball 37 is adapted to interfit with any one of a spaced series of indentations 38 in the ring 39. The ring 39 is not a part of the follower but surrounds the oil reservoir 15 and is rigidly attached to the forward end

65 of the cage or rotor 20.

The forward portion of the reservoir 15 is surrounded by the pad 40 and a similar pad 41 is placed adjacent thereto on the inner surface of the casing 14. A guide flange 42 on the inner surface of the casing 14 encircles the greater part of the cage 20 at the point where the larger series of balls 24 are placed, and a similar flange 43 of greater width but less depth is located adjacent the smaller series of balls 23. A pad 44 may 70 be placed between the flanges. The magazine is formed with an outlet opening 45 fitted with the guide flanges or lips 46 and a loading opening 47 closed by the hinged cover 48 held in place by screws 49. The 80 delivery guide 50 is placed inside the magazine adjacent the outlet opening 45 as shown in Fig. 2.

The magazine is retained upon the stock 51 by means of the forward and rear retaining devices 52 and 53 respectively. The forward device 52 is provided with the lug 54 adapted to fit in the opening 55 in the forward end of the magazine, and with the downwardly extending notches 56 adapted 85 to receive the necks of the headed studs 57 which extend from the forward face of the magazine. The rear retaining device 53 is provided with the pivot catch 58 normally held in locked relation by the spring 59, as 90 best shown in Fig. 1.

The actuating cup 26 has an outer portion knurled to facilitate manual operation at 60 and is notched at 61 to receive the spring catch 62. This catch is pressed into 100 engagement with the cup 26 by the spring 63 acting against the pin 64.

The clip loading device 65 is fastened to the stock adjacent the rear end of the magazine, and above the rear end of the opening 105 47 by the screw 66 as shown in Fig. 2. This device 65 as shown in Fig. 6 is provided with the loading slot 67, the upper end of which is notched at 68 to receive the end of a cartridge clip.

110 The magazine is attached to the gun by placing the studs 57 under the notches 56, and moving the rear upward, the opening 55 fitting over the stud 54 and the pivot 19 slipping past the catch 58. By rotating the cup 115 26 against the spring 30 the follower is moved clockwise beyond the loading opening and the catch 62 retains it in position. Cartridges are now fed into the loading opening 47, the cover 48 being opened for 120 that purpose. Each cartridge as it is pressed into place takes position between pairs of balls 23 and 24 and also contacts with the inner pad 22 between the bars 21 as shown in Fig. 2. As succeeding cartridges are 125 pushed into the magazine the cage 20 rotates since it is connected with the follower by only the yielding engagement of the ball 37 with the indentations 38, which yields and permits the cage to move the width of 130

- a cartridge seat as each is pressed in. The individual cartridges are free to rotate upon the balls and are rotated due to friction against the guide-flanges 42 and 43 and all parts of the cartridges are wiped against the several outer and inner pads and are thus thoroughly lubricated. The pads are kept constantly oiled by oil passing from the reservoir through the small ports 15'. 5
- 10 These ports also oil the bearings of the cage or rotor 20 upon the reservoir. The reservoir may be filled when necessary through the valve 18, its capacity being great enough, however, to render refilling necessary only after firing a large number of 15 rounds. After any desired number of cartridges up to its capacity have been placed in the magazine the catch 62 is released and the follower rotates under impulse of the 20 spring 30 until the pusher 34 contacts with the last cartridge as shown in Fig. 2. The pressure of the pusher forces the first cartridge up between the lips 46 as shown in Figs. 1 and 2 in which position it may be 25 carried forward by the breech closure (not shown) of the gun. When it is removed in this manner the next cartridge is carried forward into its place by the constant pressure of the follower. Additional cartridges 30 may be placed in the magazine at any time when either partially or completely empty, regardless of the position of the breech closure. The follower is rotated backward until it catches, carrying with it the rotor 35 20 through its yielding connection. The cartridges are then inserted and the follower released, when it will carry all the cartridges around as before.
- It is in reloading before all cartridges 40 have been fired that the yielding ball catch 37 is most important since its engagement is sufficient to rotate backward the cage and cartridges remaining in the magazine. The follower being held by the catch 62, the 45 catch 37 yields as additional cartridges are fed into the magazine and the rotor or cage 20 rotates away from the follower. The engagement of the cartridges between pairs of balls is such as to prevent cartridges slipping past the cage and were the reverse rotation of the cage not made before reloading when partly empty, vacant spaces would remain in the magazine. 50
- The showing of Fig. 1 makes clear the relation of the magazine to the gun and it will be seen that the extension beyond the normal gun contour is not great, and its shape is much less awkward than that of a box magazine of equal capacity. 55
- 60 We claim:
1. A magazine for use with guns, a lubricant reservoir associated with the magazine and means adapted to positively lubricate cartridges placed in the magazine.
  2. A magazine for use with guns, a lubricant reservoir and lubricating means associated with the magazine and cartridge supporting means adapted to permit rotation of the cartridge during travel in the magazine. 70
3. A magazine for use with guns, a lubricant reservoir and lubricating means associated with the magazine and cartridge supporting means adapted to permit rotation of the cartridge during travel in the magazine, the lubricating means adapted to contact with the cartridges during their rotation. 75
4. A rotary magazine for use with guns, containing a lubricant reservoir, a rotor having lubricating means therein in communication with the reservoir, and supporting means for cartridges adapted to support the cartridges in contact with the lubricating means. 80
5. A cylindrical magazine for use with guns, the magazine containing a central lubricant reservoir about which the cartridges are adapted to pass and lubricating means in communication with the reservoir and adapted to contact with the cartridges. 85
6. A rotary magazine for use with guns, a lubricant reservoir associated therewith, the magazine containing a rotor having lubricating means therein in communication with the reservoir and anti-friction supports adapted to maintain the cartridges in contact with the lubricating means. 90
7. A rotary magazine for use with guns, a lubricant reservoir associated therewith, the magazine containing a rotor having lubricating means therein in communication with the reservoir and ball supports for cartridges adapted to support cartridges in contact with the lubricating means, and to permit them to be rotated. 95
8. A rotary magazine for use with guns, having a central rotor, cartridge seats on said rotor and guides encircling the rotor and adapted to contact with cartridges and rotate them upon the seats. 100
9. A rotary magazine for use with guns, having a central rotor, cartridge seats on said rotor, guides encircling the rotor and adapted to contact with cartridges and rotate them upon the seats, and lubricating means adapted to contact with the cartridges during their rotation. 115
10. A rotary magazine for use with guns, having a central rotor, anti-friction cartridge-seats on said rotor, guides encircling the rotor and adapted to contact with cartridges and rotate them upon the seats, and lubricating means carried by the rotor between said seats, adapted to contact with the cartridges during their rotation. 120
11. A rotary magazine for use with guns, having a central rotor, anti-friction cartridge seats on said rotor and guides encircling the rotor and adapted to contact with 130

- cartridges and rotate them upon the seats, a lubricant reservoir located centrally of the rotor, and lubricating means in communication with the reservoir and adapted to contact with the cartridges upon the seats.
12. A cylindrical magazine, a cylindrical lubricant reservoir concentric therewith and a cartridge carrying rotor surrounding the reservoir and adapted to rotate thereon.
- 10 13. A cylindrical magazine, a cylindrical lubricant reservoir concentric therewith and a cartridge carrying rotor surrounding the reservoir and adapted to rotate thereon, the rotor carrying lubricating means in communication with the reservoir and adapted to contact with cartridges carried by the rotor.
14. A magazine for use with guns, a cylindrical lubricant reservoir located there-
- 20 in, a cartridge carrying rotor surrounding the reservoir and adapted to rotate thereon and ducts leading from the lubricant reservoir to the points of contact between rotor and reservoir.
- 25 15. A magazine for use with guns, a cylindrical lubricant reservoir located therein, a cartridge carrying rotor carrying lubricating means and surrounding the reservoir and adapted to rotate thereon and ducts leading from the lubricant reservoir to the points of contact between rotor and reservoir, and to the lubricating means.
- 30 16. A rotary cartridge magazine for use with guns comprising a cartridge carrying rotor, a rotary follower and a yieldable connection between the cartridge carrying rotor and the follower.
- 35 17. A rotary cartridge magazine for use with guns comprising a cartridge carrying rotor, cartridge seats upon the rotor, a rotary follower and means adapted to yieldably connect the follower to the rotor at such points that it will contact with cartridges upon the seats.
- 40 45 18. A rotary cartridge magazine for use with guns comprising a rotor having cartridge seats thereon, indentations upon one end of the rotor and having the same spacing as the seats and a rotary follower having a spring pressed plunger adapted to yieldably interfit with any one of said indentations.
- 50 55 19. A rotary cartridge magazine for use with guns comprising a rotor having cartridge seats thereon, indentations upon one end of the rotor and having the same spacing as the seats and a rotary follower having a spring pressed plunger adapted to yieldably interfit with any one of said indentations, the follower being so spaced with relation to said plunger as to be adapted to contact with a cartridge in one of said seats when the plunger is engaged in one of said indentations.
- 60 65 20. A cartridge magazine for use with guns, comprising a cartridge carrying rotor and a spring pressed rotary follower, the follower being adapted to rotate the rotor by means of pressure transmitted through cartridges carried thereby.
- 70 21. A cartridge magazine for use with guns, comprising a cartridge carrying rotor and a spring pressed rotary follower, the follower being adapted to rotate the rotor by means of pressure transmitted through cartridges carried thereby, and cartridge guide and discharge lips adapted to limit the rotary movement of a cartridge.
- 75 22. A cartridge magazine for use with guns, comprising a cartridge carrying rotor, a rotary follower and means external of the magazine adapted to permit manual rotation of the follower.
- 80 23. A cartridge magazine for use with guns comprising a cartridge carrying rotor and a rotary follower, means adapted to limit the rotary movement of the cartridges carried by the rotor and to thereby limit movement of the rotor and a yieldable connection between rotor and follower whereby movement of the follower is normally transmitted to the rotor, the yieldable connection permitting independent movement of the follower when motion of the rotor is stopped.
- 85 90 24. A cartridge magazine for use with guns comprising a cartridge carrying rotor and a rotary follower, means adapted to limit the rotary movement of the cartridges carried by the rotor and to thereby limit movement of the rotor and a yieldable connection between rotor and follower whereby movement of the follower is normally transmitted to the rotor, the yieldable connection permitting independent movement of the follower when motion of the rotor is stopped, and spring means adapted to keep the follower normally in contact with the rearmost cartridge in the magazine.
- 95 100 105 25. A cartridge magazine for use with guns comprising a cartridge carrying rotor and a rotary follower, means adapted to limit the rotary movement of cartridges carried by the rotor and to thereby limit movement of the rotor, a yieldable connection between rotor and follower whereby movement of the follower is normally transmitted to the rotor, the yieldable connection permitting independent movement of the follower when motion of the rotor is stopped, and a spring catch adapted to retain the follower at one end of its movement when loading the magazine.
- 110 115 120 125 26. A cylindrical magazine for use with guns comprising a cylindrical casing, a cylindrical lubricant reservoir located centrally thereof, a rotor rotating about said reservoir having anti-friction seats for cartridges and lubricating means in said seats adapted to transmit lubricant from the

reservoir to cartridges in the seats, and means adapted to contact with the cartridges during their movement with the rotor and to rotate each cartridge upon its seat whereby it is lubricated throughout its circumference.

27. A cylindrical magazine for use with the guns comprising a cylindrical casing, a cylindrical lubricant reservoir located centrally thereof, a rotor rotating about said reservoir having ball bearing seats for cartridges and lubricating means in said seats adapted to transmit lubricant from the reservoir to cartridges in the seats, guides

adapted to contact with the cartridges during their movement with the rotor and to rotate each cartridge upon its seat whereby it is lubricated throughout its circumference, a delivery opening, cartridge stop means adjacent thereto, and a spring pressed rotor adapted to contact with the rearmost cartridge in the magazine and thereby rotate the rotor until the first cartridge contacts with the cartridge stop means.

Signed by us at Boston, Massachusetts, 25 this 10th day of May, 1920.

JOHN TALIAFERRO THOMPSON.
